United States Patent Office

Des. 182,993
Patented June 10, 1958

182,993

BUILDING PANEL

Harold A. Edmondson, Los Angeles, Calif.

Application April 30, 1956, Serial No. 41,251

Term of patent 14 years

(Cl. D13—1)

FIG. 1.

FIG. 2

FIG. 3.

Figure 1 is a top plan view of a building panel showing my new design;

Figure 2 is a bottom plan view showing approximately three-fourths of the panel illustrated in Figure 1; and

Figure 3 is an edge elevational view as seen from the top of Figure 1.

I claim:

The ornamental design for a building panel, substantially as shown.
